J. E. DEKKER

CAN OPENER

Filed Dec. 1, 1922

Patented Feb. 24, 1925.

1,527,581

UNITED STATES PATENT OFFICE.

JOHN E. DEKKER, OF CHICAGO, ILLINOIS.

CAN OPENER.

Continuation of application Serial No. 564,878, filed May 31, 1922. This application filed December 1, 1922. Serial No. 604,276.

To all whom it may concern:

Be it known that I, JOHN E. DEKKER, a citizen of the United States, and a resident of Chicago, county of Cook, and State of Illinois, have invented certain new and useful Improvements in Can Openers, of which the following is a specification.

The general object of my invention is to provide a can opener wherewith cans can be opened quicker, easier and safer.

Another object of my invention is to provide a can opener, which shall be adapted to open cans that vary through a wide range of sizes and wherein adjustment for use in opening different sized cans can be accomplished almost instantly.

Again I aim to provide a can opener which in operation shall shear the metal and turn down the severed edge portion of the can in such manner that a clean, relatively smooth, edge shall result, thus eliminating danger of injury to those handling the can.

Other objects of my invention are to provide a can opener of simple construction; one which can be produced at low cost; one that shall be durable and particularly one in which the can shearing element shall be adapted to withstand for a long period of time the shearing of the metal and still retain its proper shearing action.

This application is a continuation of my application, Serial Number 564,878 filed May 31, 1922, entitled Can openers.

My invention consists generally in a device of the form, arrangement, construction and co-operation of the parts, whereby the above named objects, together with others that will appear hereinafter are attainable; and my invention will be more readily understood by reference to the accompanying drawings which illustrate what I consider, at the present time, to be the preferred embodiment thereof.

In said drawings:

Fig. 1 is a side elevation of a can opener embodying my invention.

Fig. 2 is a top plan view of the can opener, being illustrated in connection with the operation of opening the can.

Fig. 3 is a detail sectional fragmentary view of the can opener positioned in the can.

Fig. 4 is a sectional view substantially on the line 4-4 of Fig. 1; and

Fig. 5 is an enlarged view, not to scale, in elevation of the cutter or shear element

and the angles of the cutting edges better to illustrate features that I have found important, the dimensions of the cutter being shown in order better to illustrate the structural characteristics thereof.

The device, as here shown, is composed of four general parts or portions, to wit, a can piercing portion 1, a shear guiding and supporting portion 2, a handle 3 into which the portion 2 extends, and in which it is suitably fastened, and a shear element 4.

The handle portion 3 may obviously vary in size, shape and other characteristics, but I have thus far found a handle of the size and general shape shown to be satisfactory.

It is preferably made of wood and provided with a suitable ferrule 5. The can piercing portion 1 may likewise vary in size and shape, but I prefer to make it with an extreme end point or portion 6 which extends generally in the direction of the shear support and guiding portion 2, but which is offset with respect thereto.

The portion 6 is connected to the end of the portion 2 by means of the angularly disposed portion 7.

The under face of the can piercing portion is preferably curved throughout as indicated at 8 so that in piercing the can it can more easily be swung as is necessary to bring it from the initial piercing position to the position in which the can opener operates during the shearing operation.

On the upper side, however, the can piercing portion is preferably provided with a rather abrupt portion 9, the purpose of which is to keep the hole in the can from being reamed too large; and to prevent the point from being ripped out during operation.

The shear member 4, as here shown, is composed of a hub portion 10 and two annular flange portions 11 and 12. The flange 11 is provided with faces 13 and 14, respectively, and the flange 12 with faces 15 and 16, which throughout the greater part thereof occupy parallel positions. In other words, the flanges are substantially of the same thickness throughout. For convenience the faces 13 and 16 will be referred to as the outer faces of the flanges 11 and 12, respectively, and the faces 14 and 15 the inner faces thereof.

The distance between the inner faces of the flanges I have found to be a matter of great importance because unless properly sized, the device would operate unsatisfactorily. For example, if too close, it

will pinch, will be obstructed by vertical can seam, may be run off the can, and will work extremely hard. On the other hand, if too wide, will leave a rough edge, and will not cut the entire cover but will leave a hinge portion. That is to say, the shearing action which I desire would be destroyed. The best spacing of the faces 14 and 15 that I have thus far determined is approximately .100 of an inch. I prefer to make the cutting flanges approximately .048 of an inch in thickness.

The shape of the periphery of the flanges is important inasmuch as they are called upon to perform several different functions, that is to say, the one in use must progressively shear the cover metal, must turn it away in such a manner as to permit free movement thereof and should shear the metal of the can so cleanly that a smooth edge will result. The shape of the shear element 4 and particularly the cutting edges thereof, is probably best shown in Fig. 5, wherein it will be observed that adjacent the periphery is a beveled portion 19, and the other side is a relatively abruptly beveled portion 20. In order that the details of construction, which are extremely important, shall be better understood I have applied the dimensions and angles to the drawing. The other flange 12 is similarly constructed as that when the flange 11 has become dull after a long period of use the shearing element can be removed from the guide 2, reversed and replaced. To remove the shear element the handle can be removed. By providing a reversible shear element the potential life of the device is doubled.

One flange only operates at any one time as a shearing flange while the other operates as a guiding flange.

The external diameter of the hub 10 is preferably about $\frac{7}{16}$ of an inch and it is provided with a central bore or opening 21 which is larger in size than the size of the guiding portion 2, upon which it slides. As here shown, the guiding portion 2 is $\frac{3}{32}$ of an inch in diameter so that the opening 21 should be approximately .290 of an inch. That is to say, I want the cutter 4 not only to slide freely on the guide rod 2, but also desire a certain intervening space, the function of which will appear from the following description of the operation of the device.

Adjacent the outer end of the portion 2 is an annular portion 22, which, as here shown, is permanently secured to the member 2, the purpose of which is to prevent the shear element from slipping off the end adjacent the point.

I shall now describe the operation of the device. It is first positioned vertically, as indicated by means of dotted lines in Fig. 3,

and then pressed downwardly so that the point 6 pierces the top 23 of the can. The device is then swung downwardly to the full line position shown in Fig. 3, thus positioning the portion 6 under the cover 23 and with the edge portion 24 of the hole formed by the piercing of the cover in abutment with the relatively abrupt corner 9 of the can piercing portion.

As the device is swung downwardly the shear 4 is moved along the guide 2 until the shearing flange 11 thereof is just inside the side wall 25 of the can, so that further downward pressure causes the shearing flange to shear the cover 23 as is well shown in Fig. 3. The device is pressed downwardly until the hub 10 of the shear element comes into contact with the upper edge or bead 26 of the can. The dimensions of the parts are such that when the hub strikes the top seam of the can the shear will be found to project approximately $\frac{1}{16}$ th of an inch into the can cover. This places but a small part of the circumference of the shear in the can cover. That is to say most of the diameter thereof is outside the can. By thus inserting only a relatively small part of the shear in the can cover a true shearing action can be obtained. If any great part of the shear were inserted into the can the shearing action would be practically destroyed because in order to advance the shear around the can cover it would be necessary to plow or rip its way. This, of course, would make it extremely hard to operate and would result in quickly destroying or wearing away the edge of the cutter. It should be mentioned that before the shearing flange 11 shears the top of the can and as the pressure is applied to cause shearing thereof the device is in effect a lever which tends to swing the end portion 1 of the device upwardly, which causes movement of the can top 23 from its initial flat condition, shown by means of dotted lines in Fig. 3, to the slightly upwardly curved or cambered condition shown by means of full lines in Fig. 3. This action would cause the flanges of the shear element 4 to assume non-parallel relations to the side wall 25 of the can which would be undesirable as the shearing action would be somewhat impaired. As before stated, however, I provide some space between the support or guide 2 and the bore of the shear element 4, so that when this space is taken up by the downward movement of the shear element, it is finally positioned with the flanges thereof substantially parallel to the adjacent side or vertical wall of the can.

Having positioned the device in the full line position shown in Fig. 3 the complete cover can be quickly and easily severed by simply swinging the device around the can. The shear element is free to rotate which

not only makes easy the shearing of the metal but also results in greatly adding to the life of the element 4. The life of the shearing flanges is further increased by the 5 very novel shaping of the outer or edge portions thereof. It should be noted that the angle between the faces 19 and 20 is ninety degrees, thus providing a right angle construction which will stand up almost 10 indefinitely.

From the foregoing, it should be apparent that cans of widely different sizes can be opened with my device and that the only adjustment required is the sliding of the element 4 upon the element 2. Once the element 4 is positioned, it automatically maintains its proper position for the shearing of the can. There are no set screws or other parts that need to be adjusted and there are 15 no loose or movable parts that can be misplaced, lost or broken. The device here shown is one which takes in practically all sizes of cans in general use. The parts are all simple and hence can be produced at low 20 cost; they are also rugged in character and hence durable. In use the device has proven to be remarkably efficient and to remove the cover of the can in a clean-cut and hence 25 very desirable manner.

30 The many advantages of my device will be apparent to those skilled in the art to which this appertains without further comment.

I claim:—

35 1. A device of the kind described embodying therein, a shear guide and a shear element rotatively mounted thereon, said element including a circular disc having two faces and a peripheral cutting edge defined 40 by oppositely beveled surfaces, the plane of the cutting edge being arranged closer to the plane of that face of the disc normally disposed adjacent the bead of a can than it is to the plane of the other of said faces, 45 that beveled surface between the cutting edge and said last mentioned face of the disc being of a lesser angle than the other beveled surface.

50 2. A device of the kind described embodying therein, a shear guide and a shear element rotatively mounted thereon, said element including a circular disc having two faces and a peripheral cutting edge defined by oppositely beveled surfaces, the plane 55 of the cutting edge being arranged closer to the plane of that face of the disc normally disposed adjacent the bead of a can

than it is to the plane of the other of said faces, that beveled surface between the cutting edge and said last mentioned face of the disc being of a lesser angle than the other beveled surface, and the angle between said oppositely beveled surfaces being substantially a right angle. 60

3. A device of the kind described embodying therein, a shear guide and a shear element rotatively mounted thereon, said element including a circular disc having two faces and a peripheral cutting edge defined by oppositely beveled surfaces, the plane of the cutting edge being arranged closer to the plane of that face of the disc normally disposed adjacent the bead of a can than it is to the plane of the other of said faces, that beveled surface between the cutting edge and said first mentioned face of the disc approximately an angle of substantially sixty-five degrees with reference to the axial plane of the shear element and the other beveled surface approximating an angle of substantially twenty-five degrees to said plane. 70

4. A device of the kind described embodying therein, a shear guide and a shear element rotatively mounted thereon, said element including a circular disc having two faces and a peripheral cutting edge defined by oppositely beveled surfaces, the plane of the cutting edge being arranged closer to the plane of that face of the disc normally disposed adjacent the bead of a can than it is to the plane of the other of said faces, said shear element having a hub, the outer periphery of which is spaced radially inward substantially $\frac{1}{16}$ ths of an inch from 80 said cutting edge. 90

5. A device of the kind described embodying therein a shear guide and a circular shear element including two disc members having parallel surfaces spaced substantially to engage opposite sides of the bead of a can, one of said discs having a peripheral cutting edge which by virtue of the spacing of said disc members operates as a shear in conjunction with the adjacent inner surface of the bead of a can, a hub portion extending between said disc members, said hub being spaced radially inward from the peripheral cutting edge, riding upon the bead of the can and thereby limiting the cutting edge to but slight projection below the cover of the can to be opened. 100

In testimony whereof, I have hereunto set my hand, this 29th day of November, 1922.
JOHN E. DEKKER.
